UNITED STATES PATENT OFFICE.

DAVID HOLGE, OF CHICAGO, ILLINOIS.

KNOCKDOWN COT.

SPECIFICATION forming part of Letters Patent No. 634,665, dated October 10, 1899.

Application filed April 17, 1899. Serial No. 713,322. (No model.)

To all whom it may concern:

Be it known that I, DAVID HOLGE, a citizen of the United States, residing at Chicago, in the county of Cook and State of Illinois, have 5 invented certain new and useful Improvements in Knockdown Cots, of which the following, when taken in connection with the drawings accompanying and forming a part thereof, is a full and complete description, 10 sufficient to enable those skilled in the art to understand, make, and use the same.

Figure 1 is a side elevation of a cot embodying the invention; Fig. 2, an end elevation thereof; Fig. 3, an end elevation thereof 15 with the canvas removed and the frame folded; Fig. 4, a side elevation with the canvas removed and the frame folded, as in Fig. 3; and Fig. 5, a side elevation, on an enlarged scale, of the joining of the bars forming a side 20 rail of the canvas.

The principal object of this invention is to obtain a knockdown cot in which the canvas may be removed from the frame, and such frame can thereupon be folded into small 25 space and one convenient for shipping, a knockdown cot whereof the frame when in position for use with the canvas thereon will be strong, not liable to break when the bed thereon is used by a heavy person, and a 30 knockdown cot which is readily changed from its arrangement of parts for use into condition for shipping.

A reference-letter applied to designate a given part is used to indicate such part 35 throughout the several views wherever the same appears.

Fig. 1 shows the side rail A, supported on the three sets of legs or three horses B B B, connected together by the tie-rods C C^o. The 40 benches or horses B B are constructed of the parts or legs b b', pivotally joined together midway of their length at b², as by a bolt, as is clearly illustrated in Figs. 2 and 3. The tie-rods C C^o are pivotally attached at their 45 ends by means of the interposed hinge D (illustrated in Figs. 6 and 7) to the parts or legs b b', respectively.

The arrangement and comparative length of the legs b b' and the tie-rods C C^o are such 50 that when the legs are pivotally turned from the position thereof in Figs. 1 and 2 to the position thereof in Figs. 3 and 4 the legs form

ing or constituting one bench or horse B are drawn or lie adjacent to the legs forming or constituting the adjacent bench or horse B, 55 as is well illustrated in Fig. 4 of the drawings, and when the legs forming or constituting one horse or bench B are in the position illustrated in Figs. 1 and 2 such tie-rods C C^o force and rigidly or firmly hold such benches or horses 60 in the relative position illustrated in Fig. 1.

To accomplish the above-recited result, I construct three benches or horses B B B and attach a tie-rod, by means of the interposed hinge D, to one end of one leg of one bench 65 or horse, as, say, leg b, and to the other "leg," as it may properly be termed, of the next adjacent bench or horse, as, say, b', and, the legs b b' being at least of the length of the tie-rods C C^o, so positioning the point of attachment of the hinges D D to the respective legs that when the legs are in the position illustrated in Fig. 3 the tie-rods are of the proper length to extend in the manner shown in Fig. 4.

In the arrangement of the legs forming or 75 constituting the benches or horses which I have illustrated and the tie-rods joining them together and holding them firmly in place tie-rod C is secured at one end to leg b and at the other end to leg b' of the adjacent bench 80 or horse, and tie-rod C^o is attached at one end to leg b' and at the other end to leg b of the adjacent bench or horse.

E E are hooks attached, respectively, to the ends of the legs b b' in position so that the 85 hooks or loops F F may be respectively engaged therewith when the cot is to be placed in use.

G is the canvas (which may be of woven wire, of cotton fiber, or of other suitable material) on which the mattress or blankets forming the bed is laid. Canvas G may be attached to rails A A in the ordinary way; but I prefer to make each of the rails A A or two side bars joined together at the central horse 95 or bench. To do this, I make rail A of bars a a', and to one of such bars—say a—I attach casting A', having a socket in one end thereof, into which the bar a' fits, as is well illustrated in Fig. 5.

F is a metal loop extending through bar a and casting A', securing the casting in place, at the same time securing such loop F in place, so that when it is secured to hook E of the

central bench or horse (the strain at such bench or horse being greater than on the end benches or horses) the rail A will not be readily broken by the strain on loop F.

5 Additional loops F F are placed on the rails A A, near the ends thereof, to engage with the hooks E E on the end horses or benches B B.

When the cot embodying this invention is 10 in position for use as a bed, the canvas G prevents spreading of the legs b b', forming the horses or benches B B B, respectively, because of the rails A A being secured (by loops F F or their equivalent) to the hooks E E, as hereinbefore described, and the tie-rods C C⁰ prevent any swaying of such benches or horses. The knockdown cot thus obtained is therefore firm and strong and not liable to 15 get out of order.

20 In order to obtain a pillow, particularly when canvas woven of cotton fiber is used for the cot-bed, I extend such canvas beyond the rails A A, as at II, Fig. 1, and provide pins or other fastenings I, to which such extension

25 II may be secured. The clothing of the person using the cot for a bed may be folded and placed at the end of the canvas G and part II then brought over into substantially the position thereof illustrated in Fig. 1 and se-

cured in place. Not only is a pillow thus obtained, but also the clothing so placed under the part II is in position to disturb the user of the cot if any effort is made to abstract such clothing.

If preferred, the pillow may be obtained by 35 putting hay, straw, or other suitable substance under the part II in place of clothing.

I prefer to use flat bar-iron for the tie-rods C C⁰ and to pivotally join or tie such tie-rods together, as by the pivot or pin J, Fig. 1. 40

Having thus described my invention, what I claim as new, and desire to secure by Letters Patent, is—

In a knockdown cot, the combination of a 45 canvas, side rails to which the canvas is secured, such side rails comprising, respectively, bars, a metal band secured to one bar to extend beyond it and forming a socket in which the end of the remaining bar fits, and metal loops extending through the side rails, 50 the loop midway of the side rail also extending through the metal band; substantially as described.

DAVID HOLGE.

In presence of—

JOHN KATSKE,
O. C. PETERSON.
